UNITED STATES PATENT OFFICE.

LEO A. BRIGEL, OF CHEVIOT, OHIO.

BOTTLE-CAPPING APPARATUS.

Application filed August 23, 1920. Serial No. 405,470.

To all whom it may concern:

Be it known that I, LEO A. BRIGEL, a citizen of the United States, residing at Cheviot, in the county of Hamilton and State of Ohio, have invented certain new and useful Improvements in Bottle-Capping Apparatus, of which the following is a specification.

My invention relates to improvements in bottle capping apparatus. One of its objects is to provide an improved adjustable bottle capping apparatus. Another object is to provide improved clamping means to clamp the capping head to its adjusted positions. Another object is to provide a capping apparatus in which the capping plunger has a greater range of movement to a single setting of the head. Another object is to provide improved means to center the bottles. Another object is to provide improved means to hold the capper head and bottle in alignment. My invention also comprises certain details of form combination and arrangement all of which will be fully set forth in the description of the accompanying drawings, in which:

Fig. 1 is a side elevation partly in central vertical section, illustrating my improved apparatus.

Fig. 2, is a plan view of the same.

Fig. 3, is a sectional detail on line 3—3 of Fig. 1.

The accompanying drawings illustrate the preferred embodiment of my invention in which 14 represents the base and 15 a vertical cylindrical standard rigidly attached to said base, as for instance by a drive fit in a recess 16 in the base and then heading over the lower end of the standard at 17. The base is adapted to be rigidly fastened to a bench or similar support by means of screws 18. The standard 15 has a key-way 19 cut along one side for a considerable distance. A head 20 is bored at 21 and 22 and further recessed at 24 to permit the passage of the standard endwise through the head and the head is adjustable vertically upon the standard and adapted to be clamped rigidly thereto at different positions by means of a cam 25 journaled upon a pin 26, to the ears 27.

The face of the cam travels in and engages the key-way to both prevent the head 20 moving rotatably relative to the standard and to lock the head rigidly to the standard at any desired height. A hand lever 28 serves to actuate the cam 25 to lock or re-

lease the head 20. It is designed in locking the head 20 to the standard that the standard shall fit rather closely in bored sections 21 and 22 and loosely in the recessed section 24 and that the action of the cam 25 near the center of the recessed section will serve to slightly spring the standard opposite the cam and thus cant the snugly fitting bored sections of the head to more firmly lock the head to the standard with a relatively light pressure, on the lever 28, than would be otherwise possible.

A hand lever 29 is pivotally attached to ears 30 on the head 20 by means of a pin 31, passing through an elongated opening 32 in the end of the hand lever. The hand lever 29 has a recess to receive one end of a plunger 33, which plunger is pivotally attached to said hand lever by a pin 34. The plunger 33 is movable vertically in a recess 35 bored in the head 20, and which the plunger closely fits. At the lower end of the plunger below the head 20 is a bottle capping head of tool 36 adapted to be forced down upon a cap seated over the mouth of a bottle and to clinch the cap to the bottle and seal up the contents of the bottle. One object is to secure as long a range of vertical movement as is conveniently attainable for the plunger to provide for capping as wide a range of bottles as possible at one adjustment of the head.

I preferably provide a self-centering support 37 for the lower end of the bottle comprising a plurality of upwardly and outwardly inclined arms on which the bottom of the bottle rests and finds its own center. The support 37 may be pivotally and detachably mounted by means of a cylindrical stud 95 28 upon the base 14 if desired, or may be rigidly attached to the base, or if desired may be replaced with a flat yielding pad.

In practice the head 20 is adjusted on the standard 15 to the desired height and clamped by the hand lever 28. A bottle to be capped is placed upon the support 37, and its mouth should come to a position slightly below the head 36. A cap is placed over the mouth of the bottle and hand lever 29 is actuated to force the head 36 down upon the cap and clinch the cap to the mouth of the bottle and thereby seal its contents. After the bottle has been sealed the hand lever 29 is lifted until a spring actuated plunger 39 engages an annular recess 40 in the face of the plunger 33 to hold the head

36, plunger 33, and hand lever 29 in the raised position Fig. 1, until another bottle is in position to be capped.

I am thus enabled to provide a relatively 5 inexpensive bottle capping apparatus in which the head is adjustable through a wide range, and is held against movement rotatably and firmly locked to the standard, and in which the capping lever and plunger have 10 a wide range of movement, and when not in use are held in elevated position ready to be actuated.

The apparatus herein illustrated and described is capable of considerable modification 15 without departing from the principle of my invention.

What I claim is:

1. A bottle capper comprising a base, a cylindrical standard having a key way, a 20 head adjustable upon said standard to and from said base, a cam lever to engage the key-way in said standard to lock said head to the standard and also to prevent the head

moving rotatably relative to said standard, a plunger mounted to reciprocate in a guide 25 on said head and provided with a capping tool, and a lever pivotally connected to said head to actuate said plunger.

2. A bottle capper comprising a base, a cylindrical standard rigidly mounted upon 30 said base and provided with a key-way, a head adjustable longitudinally of said standard, a cam lever pivotally mounted upon said head and engaging said key-way to prevent rotary movement of said head in any 35 normal position of adjustment and to lock said head to said standard, a plunger mounted in a guide recess in said head and provided with a capping tool, a hand lever to actuate said plunger, and means to yieldingly retain 40 said plunger and actuating lever in raised position when idle.

In testimony whereof I have affixed my signature.

LEO A. BRIGEL.
